UNITED STATES PATENT OFFICE.

CHARLES H. LEONARD, OF GRAND RAPIDS, MICHIGAN, ASSIGNOR, BY MESNE ASSIGNMENTS, TO KELVINATOR CORPORATION, OF DETROIT, MICHIGAN, A CORPORATION OF MICHIGAN.

UNIVERSAL WATER-COOLER CONNECTION.

Application filed October 12, 1925. Serial No. 61,876.

This invention relates to a universal water cooler connection which may be applied to cooling coils for water in refrigerators. It is the practice in connection with some refrigerators to place a coil within the same in which water may be cooled. The water is supplied to the coil either by direct connection to a water main or by inverting a water holding bottle so that water may run therefrom to the coil, the lower end of the bottle being sealed by water seal in which the lower end of the bottle is submerged. The present invention relates to a universal connection for water coolers of this character whereby either method of supplying water to the coil may be used. When the refrigerator is manufactured at the factory it is supplied with this universal connection and the customer may, without in any manner altering the construction, use either the water bottle system of supplying water to the coil or the water main connection for this purpose, there being no necessity of disassembling any parts of the construction and the application of either system of supplying water to the coil being very ready and easy.

It is a primary object and purpose of the present invention to provide a simple universal water cooling construction of this character to refrigerators and one which is readily manufactured and assembled at the factory, and which when it reaches the customer is ready for the application of either of the methods of supplying water thereto. The invention is described in the following description and shown in the accompanying drawing, in which,

Fig. 1 is a perspective view of the universal water cooler connection, a fragmentary portion of a water bottle being shown as supplying water thereto.

Fig. 2 is a like view illustrating the same, the water being supplied from a water main.

Fig. 3 is an enlarged fragmentary vertical section through said connection and illustrating a slightly different way in which the water main connection may be applied, and

Fig. 4 is a vertical view of said connection illustrating the invention applied to a refrigerator, the water being supplied from an inverted water bottle.

Like reference characters refer to like parts in the different figures of the drawing.

The refrigerator 1 of any preferred type,

has a coil 2 positioned in the upper portion 55 thereof, at its outlet lower end extending through the front of the refrigerator where it may be equipped with a suitable faucet 3 which may be turned to open the same and permit water to flow outwardly when desired. The upper end 4 of the coil has its upper end threaded, as indicated at 5, for connection with the interiorly threaded lower end of a sleeve 6 which forms one part of a fitting comprising an essential element of this 60 invention. This fitting is provided with an annular outwardly extending collar 7 a distance above its lower end, and above this collar is a second integrally formed sleeve 8 which, like the sleeve 6, is both interiorly 65 and exteriorly threaded, as shown. This fitting, comprising the two sleeves 6 and 8 with the collar 7 between them is made from a single piece of material, the sleeves being in alignment, and the fitting being located a 70 short distance below the top of the refrigerator.

A sheet metal cup 9 having a bottom 10 is located through an opening made in the top of the refrigerator. The bottom 10, at one 75 side is formed with a depressed portion 11 having an opening through it through which the downwardly extending sleeve 6 of the fitting described is passed.

A rubber ring or washer 12 is disposed between the under side of the collar 7 and the upper side of the depressed portion 11. A similar but somewhat larger rubber ring or washer 13 is located around the sleeve 6 below the depressed portion 11 against which a sheet metal washer 14 is placed, a binding nut 15 being screwed on to the lower end of the sleeve 6, thereby compressing the washers 12 and 13 and making a very secure and watertight connection of the fitting to the cup. 85 The attachment of the fitting to the cup is made prior to the connection to the part 4 of the coil on to which the sleeve 6 may be readily threaded, as is obvious. The upper end of the cup 9 may be flared outwardly 90 slightly, as indicated at 9a. The attachment of the cup to the top of the refrigerator is made by means of screws 16 passing through suitable openings in the sides of the cup, whereby the cup is securely connected and held in place with its upper edges but little if any above the upper side of the refrigerator top.

This construction when applied to a refrigerator may be used for the ready supply of water from a water bottle to the coil. That is, a bottle 17 of relatively large size is inverted and placed with its neck 18 extending into the upper end of the cup 9. The water runs from the bottle until the lower end of the neck 18 is submerged in the water in the cup, indicated at 19 in Fig. 1, thereby making a seal against further escape of water from the bottle until some is drawn off through the faucet at 3. This manner of supplying water from a water bottle to a coil is well known.

If the other system of supplying water to the coil is used, that is, by direct connection with a water main, the cup 9 is not disturbed but the water pipe 20 connected with and getting its supply from a main, is connected with the upper sleeve 8 of the fitting previously described. This may be done in two ways. For instance, in Fig. 2, a nipple 21 is screwed on to the pipe 20 at one end and at the other end screwed over the upwardly extending sleeve 8. In Fig. 3, the pipe 22, corresponding to the pipe 20 in Fig. 2, is exteriorly threaded at its lower end, as indicated at 23, and then inserted into the interiorly threaded upper end of the fitting. Either method of connecting the water pipes 20 or 22 is thus made possible by the construction shown and described.

It is evident from the foregoing that by this simple construction it is possible for a refrigerator to be used without altering the refrigerator construction for either method of water supply to the water cooling coil. The water bottle method of supply may be used and, without change or disconnection of the cup 9, a water main connection may be used as shown and described. This is a very valuable feature as the customer buying a refrigerator does not desire to disassemble or disconnect any parts from it irrespective of which method of water supply he may use, and the construction described is universal in its adaptation to either method. Furthermore, the cup serves a useful purpose when the water main pipe connection is used, serving as a receptacle to receive any small leakage which may occur when the pipe 20 or 22 is connected to the fitting. Such leakage will not be great in any case and the cup is of sufficient capacity for the purpose and if leakage does occur, it will be detected in a short time and repaired, in the meantime causing no damage as the water leaking is held in the cup.

This invention is very practical and has proved its value in use. The appended claims define the invention which is to be considered as comprehensive of all forms of structure coming within their scope.

I claim:

1. In combination with a refrigerator hav-

ing a water carrying coil located inside thereof with a terminal end extending outwardly at the front of the refrigerator and an inlet end extending upwardly, of a fitting secured to the upper end of said inlet end of the coil, 70 said fitting comprising a sleeve, having an integral outwardly extending flange between the ends of the sleeve, said sleeve being threaded externally on each side of said flange, a cup having an opening in its bottom through which the lower portion of said fitting extends, a binding nut threaded on to the lower end of the fitting and yieldable washers disposed between said nut and the bottom of the cup and between said flange 80 and the upper side of the bottom of said cup for permanently securing the cup to said fitting and making a water tight connection therewith, said cup being set into the upper part of the refrigerator through the top 85 thereof.

2. In combination with a refrigerator having a water carrying coil disposed within the refrigerator and with an upwardly extending inlet, a member attached to and extending 90 vertically from the inlet end of the coil, said member having a passage therethrough for the passage of water, a cup through the bottom of which said member passes, and means connecting the member to the cup to make a 95 secure and water tight connection, said member at its upper portion extending upwardly into said cup and being threaded to adapt it to have a pipe connection made therewith without disturbing the connection of the said 100 cup thereto.

3. In combination with a water carrying coil having an upwardly extending inlet end threaded at its upper end, of a member comprising a sleeve interiorly and exteriorly 105 threaded at both ends and formed with an annular outwardly projecting flange between its ends, said water coil having screwed into one end of said sleeve, a cup having an opening in the bottom through which the lower 110 portion of said member extends, said flange being located above the bottom of said cup, a binding nut threaded on to the lower end of said member, and means disposed between said flange and the bottom of the cup and between said nut and the bottom of said cup whereby on tightening the nut a secure and water tight connection of the member to the cup is made. 115

4. In combination with a refrigerator having a water carrying coil therein, said coil having an upwardly extending inlet end, of a cup located at the upper end of said inlet end of the coil, means attached to said cup passing through the bottom thereof and having a longitudinal passage therethrough for the passage of water, said means being secured to the inlet end of the coil, and said means at its upper end within and above the bottom of the cup extending a distance up- 120 125 130

wardly into said cup and being equipped for the attachment of a pipe thereto, substantially as described.

5. In combination with a refrigerator having a water cooling coil therein provided with an upwardly extending inlet end, of a cup located in proximity to the top of the refrigerator and secured to the inlet end of the

coil, and means for securing said cup to said inlet end of the coil, said means including an auxiliary portion extending upwardly into the cup and equipped for the attachment of a pipe thereto, substantially as described. ¹⁰

In testimony whereof I affix my signature.

CHARLES H. LEONARD.

CERTIFICATE OF CORRECTION.

Patent No. 1,688,871.

Granted October 23, 1928, to

CHARLES H. LEONARD.

It is hereby certified that error appears in the printed specification of the above numbered patent requiring correction as follows: Page 2, line 108, claim 3, for the word "having" read "being"; and that the said Letters Patent should be read with this correction therein that the same may conform to the record of the case in the Patent Office.

Signed and sealed this 19th day of February, A. D. 1929.
